Term of patent 14 years

(Cl. D44—29)

FIG. 2.

FIG. 1.

FIGURE 1 is a side elevational view of a combined funnel and dispenser device showing my new design;

FIGURE 2 is a top plan view thereof, being rotated 90° from the position of FIGURE 1;

FIGURE 3 is a side elevational view thereof, FIGURE 3 being rotated 90 degrees from the position shown in FIGURE 1; and

FIGURE 4 is a bottom plan view thereof.

The essential features of the design are shown in full lines on the drawing.

This is a continuation of my earlier filed application, Serial No. D. 77,558, of November 26, 1963, now abandoned.

I claim:

The ornamental design for a combined funnel and dispenser device, as shown and described.
